(57) **CLAIM**

The ornamental design for a dental material dispenser cartridge and tip, as shown and described.

DESCRIPTION

FIG. 1 is an isometric view of a dental material dispenser cartridge and tip showing our new design;

FIG. 2 is a rear view thereof;

FIG. 3 is a front view thereof;

FIG. 4 is a first side view thereof;

FIG. 5 is a second side view thereof;

FIG. 6 is a top view thereof; and,

FIG. 7 is a bottom view thereof, portions shown in broken lines forming no part of the claimed design.
